HUMIDIFIER AND DEHUMIDIFIER WITH
AUXILIARY UNIT

Gottlieb R. Magney, Minneapolis, Minn.

Application January 23, 1931, Serial No. 510,708
Renewed November 18, 1933

33 Claims. (Cl. 257—3)

This invention relates to a heating and humidifying, and a cooling and dehumidifying device. The desirability and the healthful features of proper humidity in the air, are now generally recognized by physicians, ventilating experts, and others. The atmosphere in living rooms, of course, is most deficient in humidity in the cooler months when the rooms are more or less closed and artificial heat is supplied. It is also now realized that it is very desirable to have a simple and efficient means for cooling the atmosphere of living rooms in the summer, when the weather is quite hot. It is also desirable at such times, to reduce the humidity when the same is excessive, so that the living rooms will be supplied with a fairly uniform degree of humidity throughout the year.

It is an object of this invention, therefore, to provide a simple and efficient device which can be used to supply heat and humidity to living rooms in the months when heat is used, and can also be used to cool and dehumidify the atmosphere of these rooms in hot weather.

It is a further object of the invention to provide a device comprising a plurality of members having spaced liquid receiving surfaces, means for heating or cooling said members, means for directing a fine spray of liquid over said members, a casing surrounding said members and means, and arranged so that air passes between said surfaces and through said spray, together with a second set of members having spaced liquid receiving surfaces with means for heating and cooling said members arranged so that said air passes between said latter surfaces after passing between the first mentioned surfaces and through said spray.

It is still another object of the invention to provide a device as set forth in the preceding paragraph, in which a series of moisture eliminators are arranged between said first and second mentioned members.

It is another object of the invention to provide a device such as set forth in the paragraph preceding the last one, the same having means for directing or forcing air upward through said casing and successively between the surfaces of said members.

These and other objects and advantages of the invention will be fully set forth in the following description made in connection with the accompanying drawings, in which like reference characters refer to similar parts throughout the several views and in which:—

Fig. 1 is a view in vertical section taken substantially on line 1—1 of Fig. 2;

Fig. 2 is a vertical section taken substantially on line 2—2 of Fig. 1;

Fig. 3 is a partial view similar to Fig. 1 shown on an enlarged scale;

Fig. 4 is a wiring diagram of controls used with the device; and

Fig. 5 is a modified wiring diagram.

Referring to the drawings, a casing 10 is shown, 10 and while this casing may be of various shapes, in the embodiment of the invention illustrated it is shown as substantially rectangular in longitudinal and transverse cross section. This casing may, of course, be ornamented as desired. Said 15 casing has a closed top and bottom and one end is shown as closed, while another end has an air inlet opening 10a therethrough. Casing 10 is shown as supported upon legs 10b arranged at the corners thereof. Within casing 10 adjacent 20 opening 10a is a fan casing 11 having therein a fan driven by a motor 12 mounted upon a base 13 which will be suitably supported at the sides of casing 10. Fan casing 11 has an opening at 25 its side 11a through which air is taken in by the fan in said casing, said air being discharged from said casing through a conduit 14 extending along the bottom of casing 10 and having a plurality of outlet openings 14a from which air issues, as indicated by the arrows in Fig. 1. Within the casing 10 is another casing designated generally as 30 15.

A radiator 16 is disposed in casing 10 at the lower portion thereof, having header members 16a and 16b between which extend the spaced tubes 16c. Header member 16a is shown as having a removable end plate 16e thereon secured by suitable bolts. This radiator is of the type shown as 23 in applicant's co-pending application Serial No. 491,466, filed October 27, 1930. 35 Tubes 16c are shown as secured in the header members by coupling members 16d. The tubes 16c extend through the casing 15, said casing having inclined end plates 15a and 15b extending in parallel relation and between which are disposed a plurality or series of members 17 having liquid receiving surfaces, said members being illustrated as in the form of thin plates. The plates 17 are shown as arranged in parallel relation to each other and to the ends 15a and 15b 40 and are supported upon the tubes 16c, said tubes passing therethrough. These plates may be supported as are the plates 27 shown in applicant's co-pending application above mentioned.

Casing 15 above and at the left of plates 17 as 55

shown in Fig. 1 is in the form of a cone 15c having its wide end directed toward the plates 17 and casing 15 has a semi-cylindrical top portion 15d, as more clearly seen in Fig. 2, extending from the conical portion 15c. Casing 15 extends upwardly and has a pair of parallel end walls 15e arranged in a zigzag plane and within which is slidably arranged a member 18. Member 18 comprises end plates 18a and front and rear plates 18b and 18c respectively. Plates 18a are supported on angles 18f secured to the sides of casing 15. Between the plates 18b and 18c extend a plurality of zigzag plates 18d and 18e, the same having portions extending parallel to the end walls 18a. The plates 18e are disposed at the top of member 18 and have at their top edges the angular narrow plates 19 which also extend between the front and rear plates 18b and 18c. The plates 19 have their angles substantially bisected by the plates 18e. Plates 18a have small plates at their upper ends parallel to one side of plates 19. The plates 18e have the lower portions 18f which have at their lower edges the narrow angular plates 20 which extend between front and rear plates 18b and 18c and also have their angles substantially bisected by the portions 18f. It will be seen that plates 19 have their points or apices directed upwardly while those of the plates 20 are directed downwardly. It will also be noted that the upper portion of plates 18e projects downwardly a short distance below and at the side of the tops of portions 18f. The plates 18d as shown in Fig. 1 are at the bottom of member 18 and have their lower edge portions 18i bent upwardly at an angle of substantially 60°, these small upwardly bent portions 18i forming gutters at the bottoms of plates 18d. Plate 18a at the right of Fig. 1 has a small plate at an angle thereto similar to said latter portion, also forming a gutter. Plates 18d have upper portions 18g which have at their upper ends narrow angular trough-like plates 21 having their apices directed upwardly and the angle thereof substantially bisected by the portions 18g. Plate 18a at the right as seen in Fig. 1 has a small plate aligned with and parallel to one side of members 21. The portions 18g extend downwardly somewhat below the tops of the lower plates 18d, thus forming an angle with said plates, and portions 18g have their lower edge portions 18j bent upwardly for a short distance substantially parallel to the lower portions of plates 18d, thus forming gutters at the bottoms of portions 18g. Plate 18a at the left of member 18 as seen in Fig. 1 has a similar gutter. It will be seen that the portions 18g extend upwardly between the portions 18f. Gutter portions 18j, 18i, and 20 terminate a short distance from plate 18c and over trough member 50. Plate 18a has on its front a handle 18h.

Above the portions 15e casing 15 has upwardly inclined end portions 15f and 15g parallel to each other, portions 15g being extended in the same plane by a portion 15h and an outlet conduit 15i extends from portions 15f and 15h and from the sides of casing 15, the same having an open end and extending through one end of casing 10, said outlet portion 15i being rectangular in vertical cross section.

A second radiator 22 is disposed in the upper portion of casing 10, the same being similar to radiator 16 and having header portions 22a and 22b between which extend the tubes 22c secured to the headers by suitable couplings 22d. The tubes 22c extend through the ends 15f and 15g of casing 15, and a plurality of series of members

23 having spaced liquid receiving surfaces are supported by tubes 22c, said members being shown as in the form of thin plates. Plates 23 are shown as parallel to each other and to the ends 15f and 15g of the casing. The radiators 5 16 and 22 are constructed and arranged to receive either a heating or cooling medium. The radiator 16 is supplied through a conduit 24 controlled by a solenoid valve 25 under the control of a mercoind control device 26. Tube 24 communicates with a supply pipe 27 which is connected to a supply pipe 28 which supplies cooling fluid and is controlled by the valve 29 as well as with a supply pipe 30 which supplies heating fluid and is controlled by a valve 31. A conduit 32 connects with conduit 27 and supplies fluid to the header 22b of the radiator 22, this conduit being controlled by the magnetic valve 33 in turn operated or controlled by the mercoind control device 34. A discharge or return pipe 35 leads from the header 16a of radiator 16 to a common return pipe 36, and another return pipe 37 leads from the header 22a of radiator 22 and is connected to pipe 36. Pipe 36 is connected to a return pipe 38 which is the return pipe for heating fluid and is controlled by the valve 39, and pipe 36 also is connected to the return pipe 40 which is the return pipe for cooling fluid and is controlled by the valve 41.

Water under pressure is supplied from a suitable source through a pipe 42 having a manually operable valve 42a therein, said pipe 42 being shown as passing into the header 16a and then passing through one of the tubes 16c. Said pipe 35 is of sinuous form in said tube so as to provide for expansion and contraction. Pipe 42 extends through the header 16b and then passes into a strainer member 43. From the strainer 43 a tube 44 extends to a magnetically operated valve 45 from which a tube 46 extends, the same projecting into the end of conical portion 15c of casing 15 and terminating in a spray discharge nozzle 47. A trough 48 is disposed below the plates 17, the same having transverse trough portions 48a and longitudinally extending troughs 48b at its sides, said latter troughs discharging into an end trough 48c sloping toward its center and having a discharge pipe 49 leading therefrom which extends downwardly through the bottom of casing 10. Trough 48 is substantially the same in structure as is trough 31 shown in applicant's pending application above mentioned, and said trough has openings or slots between the transverse troughs 48a as shown in Fig. 3. A 55 discharge trough or gutter 50 is also provided below the member 18 and particularly below the lower members 18d adapted to receive from the troughs formed on the lower edges of plates 18d, and from the troughs formed on portions 18g and 18f. Drain pipe 50a leads from one end of trough 50 through the casing 15 to any desired point.

In Fig. 4 a wiring diagram for the apparatus is shown, which includes the line conductors 51 and 52 which will be controlled by the main switch 53 preferably of the Square D type. A thermostat 54 will be disposed in the rooms to be heated, and this is connected to line conductor 51 and to a contactor device or control device 55 comprising low and high contacts 55a and 55b respectively and adapted to respectively control and close a pair of circuits. Device 55 has an operating magnet 55c. Thermostat 54 is connected to the line conductor 51 by a conductor 56 and is con- 70 75

5 nected to the contactor device by a conductor 57. A humidostat 58 is used, which is also connected to line conductor 51 by a conductor 59 and is connected by a conductor 60 to the solenoid 6 valve control member 45 which controls nozzle 47. The member 45 is connected by a conductor 61 to another conductor 62 which in turn is connected to the middle contact of a two-way switch 63. The switch 63 has a contact 63a connected by a conductor 64 to what is called the low contact 55a of the contactor device 55. Contact 55a is connected by conductor 65 to the line conductor 52. Switch 63 has another contact 63b connected by conductor 66 to the high contact 55b of member 55 and contact 55b is connected by conductor 67 to conductor 65 and hence to the line conductor 52. Another thermostat 68 is disposed in the rooms to be treated and is connected to line conductor 51 by a conductor 69. Said thermostat 20 is connected by a conductor 70 to the mercoil control device 34 which controls the valve 33. The device 34 is connected by conductor 71 to the conductor 62 and hence to the switch 63 and to contactor member 55. Line conductor 51 is also connected by conductor 72 to a control member or switch 73 for the motor 12 and member 73 is connected by conductor 74 to the conductor 62. Line conductor 51 is connected to or extends to another control device 26 which controls the valve 25 and member 26 is also connected to conductor 62.

In Fig. 5 a form of wiring diagram is shown, in which a three-contact thermostat 75 is used in place of the thermostat 54 shown in Fig. 4. With this thermostat a contactor member or control device 77 is used, having low and high contacts 77a and 77b respectively adapted to be connected by the movable member 77d. A conductor 76 connects the low contact 77a to the low contact of thermostat 75. A conductor 78 connects the common wire of thermostat 75 to a contact on contactor 77 and a conductor 79 connects the high contact of thermostat 75 to a contact on contactor 77 and extends through a coil 77h thereon to the operating magnet coil 77c which actuates movable member 77d. Another conductor 77g extends from magnet coil 77c to a coil 77f, and conductor 77e extends from coil 77f to high contact 77b.

In operation, when the rooms are to be heated, heating medium such as hot water or steam will be supplied to pipe 30 and valve 31 will be opened. Valve 29 at this time will be closed. When the temperature drops below a certain point, assuming the diagram in Fig. 4 is used, thermostat 54 will operate mercoil control 26 and valve 25 will be opened to permit heating medium to pass into radiator 16. This radiator, including the tubes 16c, will be heated and plates 17 will also be heated. Motor 12 will simultaneously be started by thermostat 54 and fan 11 will deliver a current of air upwardly in the casing 15, which air passes through the openings in trough 48 between the plates 17 and upwardly into the portion of the casing above said plates. When the humidity drops below a certain point, humidostat 58 will operate through the control valve 45 so that fluid under pressure will be admitted to pipe 46 and nozzle 47. However, valve 45 cannot be operated unless mercoil control 26 has already been operated.

Referring to the diagram in Fig. 4, when thermostat 54 operates upon the temperature dropping to a certain point, conductors 56 and 57 will be connected at the thermostat and current will

flow through the magnet 55c of contactor or control device 55. This can be traced from line conductor 51 through conductors 56, thermostat 54, conductor 57 and magnet 55c, and thence to line conductor 52. The contactor now operates to close the contacts 55b and current flows from the hot side of line 52 through conductors 65, 67, contacts 55, conductor 66 to contact 63b of switch 63, to the central contact of said switch, thence to conductor 62 from control members 73 and 26 and to the other line conductor 51, the current passing from member 73 to line conductor 51 through conductor 72. It will be seen that after humidostat 58 operates to close a connection between conductors 59 and 60, that current can then flow through member 45 by way of conductor 61 and conductors 60 and 59 to conductor 51. It will also be seen that unless thermostat 54 has operated to put current on conductor 62, that humidostat 58 will not be able to operate control member 45. Water cannot thus be sprayed by nozzle 47 unless there is heat in the radiator 16.

Water being admitted to nozzle 47, the same is projected in a fine mist in portion 15d of casing 15 over the plates 17. This spray is encountered by the rising current of air delivered from conduit 14 and some of the spray is evaporated and carried along with the air which moves upwardly in casing 15 and through member 18. The air must pass between the plates 18e and 18d and will encounter the small angular plates 19, 20 and 21. Should there be any fine drops or globules of water carried along in the air, they will strike the plates 18d and 18e as well as the angular baffle plates 19, 20, and 21, and will be precipitated on said plates and thus removed or eliminated from the air. The moisture thus eliminated will gather on the plates 18d and 18e and collect in the gutters formed in the bottoms of these plates, said moisture then draining downward into the trough 50. It will be noted, as clearly shown in Fig. 2, that the plates 18d and 18e, as well as the plates 19, 20, and 21, slope toward one side of casing 15. Some of the spray delivered by nozzle 47 may drop onto the plates 17 and will be distributed on said plates in a film. As the air passes over these plates, the moisture will be evaporated by the air and heat of the plates, and this moisture will also be carried along by the air. Should the moisture collect on plates 17 in sufficient quantities to run down the same, it will drain into the transverse troughs 48a from the lower edges of the plates and will pass through troughs 48b to trough 48c and out through drain pipe 49.

Thermostat 68 will also operate and will act to actuate control member 34. Referring to Fig. 4, it will be seen that with current on conductor 62, this current can pass through conductor 71, member 34, conductor 70, thermostat 68 and conductor 69 to the line conductor 51. Thermostat 68 may be set to operate at the same temperature as the thermostat 54, but preferably will be set to operate at a higher point. When control member 34 operates, valve 33 is opened and heating fluid will be delivered to radiator 22. Tubes 22c and plates 23 will thus be heated. The air passing through member 18 then passes between plates 23 and around the tubes 22c. This air is thus heated to a greater degree and this will evaporate any moisture that may yet be bodily carried along with the air and will relatively reduce the humidity carried in the air so that it is further from the saturation point. The

heated air with the evaporated moisture therein thus passes out of the discharge member 15*i* and into the rooms to be conditioned. The air thus passes from casing 15 well charged with humidity, and the air in the rooms to be conditioned will thus have the desired degree of humidity.

As stated, member 18 is slideable and this member can be moved transversely from casing 15. The member 18 can be drawn laterally from casing 15 by pulling outwardly on the handle 18*h*.

When the wiring scheme shown in Fig. 5 is used with contactor 17 and thermostat 15, thermostat 15 moves to connect conductors 16 and 18 when the temperature drops to a certain point and moves to connect conductors 18 and 19 when the temperature rises to a certain point. When the temperature drops and conductors 16 and 18 are connected, current flows from the live side of line 52 to contact 11*a*, thence through conductor 16 to thermostat 15 and back on the common wire 18 which extends to a contact on contactor 17 and passes through magnet coil 77*c* and through conductor 80 to line conductor 51. Magnet coil 77*c* operates and contact 11*a* and 11*b* are engaged by the movable member 11*d*. Current can now flow from line conductor 52 to contact 11*a* through member 11*d* to contact 11*b* and to conductor 81, thence to control member 13 and 26 and back to conductor 51, current flowing from member 13 over conductor 12. Valve 25 is thus operated and motor 12 is started. When movable member 11*d* engages contact 11*b*, current can also flow through conductor 77*e* of contactor 17 through a holding coil 77*f* and through conductor 77*g* to the magnet 77*c* and thence through conductor 80 to line conductor 51. The member 11*d* will thus be held in place even if thermostat 15 moves to separate conductors 16 and 18. With current on conductor 81, it will be seen that humidostat 58 can operate to actuate control member 45 and deliver spray to nozzle 47, current passing from conductor 81 through conductor 82, member 45, conductor 60, humidostat 58 and conductor 59 to line conductor 51. When the temperature rises to the desired point, thermostat 15 will move to connect conductors 18 and 19 and current will flow from the live side of line 52 through member 11*d*, conductor 77*e*, conductor 11*g*, through conductor 18, thermostat 15, conductor 19 and back through coil 77*h* of contactor 17 and through conductor 80 to line conductor 51. The magnet 77*c* is thus short circuited and movable member 11*d* will move away from contacts 11*a* and 11*b* and current will be cut off from conductor 81. Control device 13 will then act to stop motor 12 and control device 26 will act to close valve 25. It will be seen that while the current is on conductor 81, that thermostat 68 can operate to actuate control member 34 and open valve 33 so that heat is delivered to radiator 22.

In hot weather the device can be used to cool and dehumidify the air in the rooms. At this time valve 31 will be closed and cooling medium will be supplied through pipe 28, valve 29 being open. It may be stated that when the device is to be used as a heating and humidifying apparatus, switch 63 will be thrown so that the central contact and contact 63*b* are connected. When the apparatus is being used as a cooling and dehumidifying apparatus, switch 63 will be in position with the central contact and contact 63*a* connected. Under these conditions, when the temperature rises to a certain point in the rooms, the thermostat 54 will act as before described

to place current on conductor 62 and control device 13 and 26 will be operated. At this time the current will pass from conductor 65 to contacts 55*a* and through conductor 64 to contact 63*a* of switch 63 and thence to conductor 62.

Valve 25 will be opened, and the cooling medium will be supplied to radiator 16 so that this radiator, including tubes 16*c*, will be refrigerated or brought to a low temperature. Plates 17 will also thus be cooled. If the humidity rises to a certain point, humidostat 58 will, through control valve 45, operate to deliver liquid to the spray nozzle 47 and this spray will be directed in casing 15 as already described. It will be noted that humidostat 58 will not be able to act to have spray delivered at nozzle 47 unless controls 13 and 34 have already been operated. Motor 12 will operate and air will be delivered through the conduit 14. This air will pass between the plates 17 and around the radiator tubes 16*c* and will be brought to a low temperature and the humidity therein be reduced. The capacity of the air for absorbing moisture will, of course, be reduced and the air will pass upward through the spray and through the member 18. Member 18 will act as already described to eliminate any drops or small globules of moisture which might be in the air. The air is now well cooled and after passing member 18, is further cooled by passing between plates 23. As already described, after current is on conductor 62, thermostat 68 can act to actuate the control device 34 and open valve 33 so that cooling medium will be supplied to radiator 22. Thermostat 68 preferably is set to act at a slightly lower temperature than thermostat 54. The air passing between plates 23 and around tubes 20*c* will be further cooled and its capacity to hold moisture thus further reduced. Cool air is delivered through outlet 15*i* after passing between plates 23 and passes to the rooms to be conditioned. A cool and dehumidified air, with the humidity at the desired point, is thus discharged into the rooms. It, of course, is not desired to direct very cool air into the rooms, but the air will be desirably between 65 and 70 degrees Fahrenheit, and will have the desired degree of humidity.

The same action will be had with the wiring diagram shown in Fig. 5, the contactor 17 being actuated when the temperature rises to a certain point and the apparatus being rendered inoperative when the temperature drops to a certain point.

From the above description it is seen that applicant has provided a simple and efficient heating and humidifying, as well as a cooling and dehumidifying apparatus. The device acts to condition the air in the rooms and to insure a sufficient degree of humidity without having any excess humidity. The liquid delivered for the humidity is of small quantity and only slightly, if any, in excess of that actually required for the desired degree of humidity. The device is simple in construction and compact and can be confined in a cabinet of comparatively small size which can be inconspicuously placed in a room. The device is accurately controlled and functions automatically. As above described, a desirable and comfortable temperature is maintained in both summer and winter and a practically uniform degree of humidity is maintained throughout the year. It is apparent that the device will have a high degree of utility for the purpose intended.

It will, of course, be understood that various

changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

1. A heating, humidifying, cooling and dehumidifying device having in combination, a casing, a series of members in said casing having spaced surfaces adapted to receive and shed liquid, means for delivering a fine spray of liquid into said casing over said members, means adapted to receive a heating or cooling medium for heating or cooling said members, said casing being adapted for the passage of air therethrough, over said surfaces and through said spray, a second series of members in said casing having spaced surfaces of non-absorbent material over which said air passes after it has passed over said first mentioned surfaces and through said spray, and means for heating or cooling said last mentioned members for drying or cooling said air.

2. A heating, humidifying, cooling and dehumidifying device having in combination, a casing, a series of members in said casing having spaced liquid receiving surfaces, means for delivering a fine spray of liquid into said casing over said members, means for heating or cooling said members, said casing being adapted for the passage of air therethrough to pass over said surfaces and through said spray, a second series of members in said casing having spaced surfaces between and over which said air passes after having passed over said first mentioned surfaces and through said spray, a moisture eliminating device between said series of members through which said air passes, and means for heating or cooling said second series of members whereby said air is dried or cooled by said latter members.

3. A device of the class described, comprising a casing, a radiator in said casing, means for supplying a heating or cooling medium to said radiator, means adjacent said radiator and heated or cooled thereby, comprising spaced surfaces of relatively large area extending transversely of the general direction of said radiator and adapted to receive and shed liquid, means for delivering a fine spray of liquid into said casing so that some of said liquid may be received on said surfaces, a second radiator spaced from said first mentioned radiator, means adjacent said second radiator to be heated or cooled thereby comprising spaced surfaces of relatively large area extending transversely of the general longitudinal extent of said radiator, said casing being constructed and arranged for the passage of air therethrough through and about said first mentioned radiator between and in contact with said first mentioned surfaces, through said spray, through and about said second mentioned radiator, and between and in contact with said second mentioned surfaces, whereby said air is dried or cooled by said second radiator.

4. A device of the class described having in combination, a casing, a radiator in said casing, means for supplying a heating or cooling medium to said radiator, means for directing air through said casing and through said radiator, means for directing a fine spray of liquid into said casing, a second radiator beyond said means

in the direction of the travel of said air, thermostatic means in the rooms to be heated and humidified controlling the admission of said medium to said first mentioned radiator and controlling delivery of said spray, and means preventing delivery of said spray if said medium is not first supplied to said radiator.

5. A device of the class described having in combination, a casing, a radiator in said casing, means for supplying a heating or cooling medium to said radiator, means for directing air through said casing and through said radiator, means for directing a fine spray of liquid into said casing, a second radiator beyond said means in the direction of the travel of said air, thermostatic means in the rooms to be heated and humidified controlling the admission of said medium to said first mentioned radiator, controlling the second mentioned means, and controlling the third mentioned means, and means preventing operation of said third mentioned means if said medium is not first supplied to said first mentioned radiator.

6. An apparatus of the class described, having in combination, a casing, said casing having an inlet opening adjacent one end and an outlet opening adjacent its other end, constructed and arranged to have air pass therethrough from said inlet to said outlet opening, means in said casing adjacent said inlet opening for heating said air, members associated with said means and heated thereby, having a series of spaced surfaces, means beyond said means for directing a fine spray of liquid into said casing over said members for supplying moisture to said air, and means beyond said last mentioned means for drying said air.

7. An apparatus of the class described, having in combination, a casing, said casing having an inlet opening adjacent one end and an outlet opening adjacent its other end, constructed and arranged to have air pass therethrough from said inlet to said outlet opening, means in said casing adjacent said inlet opening for heating said air, members associated with said means and heated thereby, comprising a series of spaced surfaces, means beyond said means for directing a fine spray of liquid into said casing above said members for supplying moisture to said air, means for eliminating surplus moisture from said air, and means for drying said air to reduce the humidity thereof.

8. A humidifying device having in combination, a casing having an inlet opening for air and an outlet opening for air above said inlet opening and adjacent the top of said casing, a heat exchange element in said casing, means for delivering a fine spray or mist into said casing above said heat exchange element, a second heat exchange element beyond said spray means in the direction of air travel, and a plurality of eliminators between said spray means and said second heat exchange element.

9. A humidifying device having in combination, a casing having an inlet opening for air adjacent its bottom and an outlet opening for air adjacent its top, a humidifying unit in said casing above said inlet opening comprising a series of conduits with plates carried thereby and inclined thereto, a series of baffles above said humidifying unit, conduits adapted to receive a cooling medium disposed above said baffles, plates associated with said conduits, and means for passing air through said casing from said inlet

to said outlet opening to pass over said conduits and between said plates.

10. A humidifying device having in combination, a casing having a plurality of air inlet openings at its bottom and an outlet opening for air adjacent its top, a humidifying unit in said casing above said inlet openings, a series of baffle plates above said humidifying unit, means for forcing air through said casing from said inlet openings to said outlet opening past said humidifying unit and between said baffle plates, a plurality of conduits in said casing above said baffle plates, means for supplying a cooling medium to said conduits, a plurality of plates carried by said conduits whereby said air is supplied with moisture by said unit and passes between said baffle plates and between said conduits and last mentioned plates.

11. A humidifying device having in combination, a casing having an inlet opening for air adjacent its bottom and an outlet opening for air adjacent its top, a humidifying unit in said casing above said inlet opening, means for passing air into said casing from said inlet opening past said humidifying unit and out at said outlet opening, a cooling means above said humidifying unit, a plurality of plates below said cooling means in position to receive any moisture precipitated and dripping therefrom, and means for collecting said moisture and conveying the same from said casing.

12. A device for heating and humidifying a room, a casing, a heating element therein, means for supplying a heating medium to said element, means for passing air through said casing to be heated by said element, means for controlling the supply of heating medium to said element, a thermally actuated device in the room to be heated for actuating said last mentioned means and for starting the operation of said second mentioned means, a second heating means in said casing, means for supplying a heating medium thereto and a second thermally controlled means for controlling said last mentioned means.

13. A device for humidifying and dehumidifying a room having in combination, a heat exchange element, means including a thermostat subject to the temperature in said room for controlling the supply of a medium to said element, means for supplying air to pass over said element, means for supplying a liquid for humidification and means responsive to said first mentioned means and including a humidostat for controlling said last mentioned means.

14. A device for humidifying and heating a room having in combination, a heating element, means for supplying a heating medium thereto, means for passing air over said heating element to be heated thereby, means for controlling the supply of heating medium to said heating means, a thermally actuated device in the room to be heated for controlling said last mentioned means and simultaneously the operation of said second mentioned means, a second heating element spaced from said heating element in the direction of travel of said air, means for supplying a heating medium to said second heating element and a thermally actuated device in the room to be heated for controlling said last mentioned means.

15. An apparatus for heating and humidifying a room having in combination, a heat exchange element, means for supplying a heating medium to said element, means for controlling said last mentioned means, a control device, a

thermostat subject to the temperature of said room, means for supplying a liquid for humidification, means for controlling said last mentioned means, a humidostat, an electrical circuit closed by said thermostat for operating said control device and said second mentioned means and an auxiliary circuit including said control device, said humidostat and last mentioned means and adapted to be closed by said humidostat to operate said last mentioned means.

16. An apparatus for heating and humidifying a room having in combination, a heat exchange element, means for supplying a heating medium to said element, means for controlling said last mentioned means, means for supplying air to said room, a motor for operating said last mentioned means, a control device, a thermostat subject to the temperature of said room, means for supplying liquid for humidification, means for controlling said last mentioned means, a humidostat, an electric circuit closed by said thermostat for operating said control device, a circuit closed by said control device including said motor and an auxiliary circuit including said control device, said humidostat and last mentioned means and adapted to be closed by said humidostat to operate said last mentioned means.

17. An apparatus for heating and humidifying a room having in combination, a heat exchange element, means for supplying a heating medium to said element, means for supplying a cooling medium to said element, means for controlling the supply of said mediums to said element, a control device, a thermostat subject to the temperature in said room, means for supplying liquid for humidification, a humidostat in said room, an electric circuit closed by said thermostat for operating said control device and an auxiliary circuit including said control device, said humidostat and last mentioned means and adapted to be closed by said humidostat to control the supply of liquid.

18. An apparatus for heating and humidifying a room having in combination, a heat exchange element, means for supplying a heating or cooling medium, a control device, means for supplying a liquid for humidification, a humidostat in said room, a thermostat subject to the temperature in said room for operating said control device, said control device constituting a master or limit switch permitting operation of said last mentioned means by said humidostat.

19. The structure set forth in claim 15, a second heat exchange element and means for supplying a heating medium to said second heat exchange element.

20. The structure set forth in claim 15, a second heat exchange element, a conduit for supplying heating or cooling medium to said element, an electrically operated valve for controlling said conduit, a second thermostat subject to the temperature in said room and an electric circuit adapted to be closed by said thermostat for operating said valve.

21. An apparatus for heating and cooling a room having in combination, a heat exchange element, means for supplying a heating medium to said element, means for supplying a cooling medium to said element, an electrically operated valve for controlling the supply of said mediums to said element, an electrically operated control switch, a thermostat subject to the temperature in said room for closing a circuit to operate said control switch and an electric circuit including

said valve and said switch and adapted to be closed by the latter for operating said valve.

22. An apparatus for heating and humidifying a room having in combination, means for supplying a heating medium, means for supplying liquid for humidification, means for controlling said last mentioned means, means for discharging air into said room, a motor for operating said last mentioned means, a control switch, a 10 thermostat, an electric circuit including said control switch and said thermostat and closed by the latter for operating said switch, a circuit including and closed by contacts moved into engagement by said control switch and including 15 said motor for operating said motor and means including said switch for operating said third mentioned means.

23. An apparatus for heating and humidifying a room having in combination, a heat exchange element, means for supplying a heating medium to said element, means for controlling said means, means for supplying a liquid for humidification, means for controlling said last mentioned means, a humidostat in said room, a 20 control device and a thermostat having three conductors extending thereto for operating said control device upon the attainment of definite high and low temperatures and a circuit including contacts engaged by said device, said last 25 mentioned means and said humidostat and adapted to be closed by the latter for operating said last mentioned means.

24. An apparatus for heating and humidifying a room having in combination, means for supplying a heating medium, means for controlling said last mentioned means, a control device, a thermostat subject to the temperature of said room, means for supplying a liquid for humidification, means for controlling said last mentioned means, a humidostat, an electrical circuit 40 closed by said thermostat for operating said control device, a second circuit including said control device and second mentioned means for operating the latter and a third circuit including 45 said control device, said humidostat and last mentioned means and adapted to be closed by said humidostat to operate said last mentioned means.

25. An apparatus for conditioning the air in a room having in combination, a device for controlling delivery of liquid to a humidifier, a 50 humidity actuated regulator, connections between said regulator and said device, means for supplying a heating medium, a thermally actuated device subject to the temperature in said room and connections between said last mentioned device and said humidity actuated regulator to render the latter operative to control 55 said first mentioned device upon operation of said thermally actuated device.

26. An apparatus for conditioning the air in a room having in combination, a device for controlling the delivery of liquid to a humidifier, a 60 humidity actuated regulator for controlling said device, means for supplying a heating medium, means for discharging air into said room, a thermally actuated regulator subject to the temperature in said room, connections between said 65 thermally actuated regulator and said last mentioned means for rendering said last mentioned means operative upon operation of said thermally actuated regulator and connections between said thermally actuated regulator and said 70 humidity actuated regulator for permitting the 75

latter to control said first mentioned device upon actuation of said thermally actuated device.

27. An apparatus for conditioning the air in a room having in combination, a device for controlling the delivery of liquid for humidification, 5 a humidostat in said room adapted to control said device, means for supplying a heating medium, means for controlling said last mentioned means, a thermostat subject to the temperature in said room and connections between said thermostat 10 and second mentioned means for operating the latter and between said thermostat and humidostat to render the latter operative to control said first mentioned device.

28. An apparatus for heating and humidifying 15 a room having in combination, means for supplying a heating medium, a control device, a thermostat subject to the temperature of said room, means for supplying a liquid for humidification, means for controlling said last mentioned 20 means, a humidostat, an electric circuit closed by said thermostat for operating said control device and a circuit including said control device, said humidostat and last mentioned means and adapted to be closed by said humidostat to operate said 25 last mentioned means.

29. An apparatus for heating and humidifying a room having in combination, means for supplying a heating medium, means for supplying air to said room, a control device, a thermostat 30 subject to the temperature of said room, means for supplying liquid for humidification, means for controlling said last mentioned means, a humidostat in said room, an electric circuit closed by said thermostat for operating said control 35 device and said second mentioned means and a circuit including said control device, said humidostat and last mentioned means and adapted to be closed by said humidostat to operate said last mentioned means.

30. An apparatus of the class described, having in combination, a casing, a radiator in said casing comprising a series of spaced surfaces extending across said casing, said casing having an inlet opening adjacent its lower end and an 45 outlet opening adjacent its upper end and constructed and arranged to have air passed therethrough, said casing having a chamber above 50 said radiator, means for directing a fine spray of liquid into said chamber and over said radiator, a second radiator above said means also comprising a series of spaced surfaces extending across said casing and inclined to the general direction of the travel of said air as it engages 55 said surfaces, and means for supplying a heating or cooling medium to said second radiator for drying or cooling said air.

31. The structure set forth in claim 4 and a second thermostatic means in the rooms to be heated controlling delivery of said mediums to 60 said second radiator.

32. A heating, humidifying, cooling and dehumidifying device having in combination, a casing, a heat exchange element in said casing, means for supplying a heating or cooling medium 65 to said heat exchange element, evaporating means extending along and above said heat exchange element and heated or cooled thereby, means for projecting a fine mist over said evaporating means whereby said mist may fall on the 70 latter, said casing having an inlet opening for air below said heat exchange element, a second heat exchange element above said evaporating means, means for supplying a heating or cooling medium to said second heat exchange element, 75

and an outlet opening for air beyond said second heat exchange element, said second heat exchange element acting to cool or dry said air.

33. A humidifying device having in combination, a casing having an inlet opening for air adjacent its bottom and an outlet opening for air adjacent its top, a heat exchange element in said casing adjacent the lower portion thereof, a sec-

ond heat exchange element adjacent the upper portion of said casing, a plurality of plates disposed between said heat exchange elements, means for passing air through said casing, and means for collecting moisture precipitated from said plates and conveying the same from said casing.

GOTTLIEB R. MAGNEY.
